ADJUSTABLE INDUCTORS

James H. Walker, Hermitage, Tenn., assignor to Aladdin Industries, Incorporated, Chicago, Ill., a corporation of Illinois

Filed Apr. 29, 1963, Ser. No. 276,620
1 Claim. (Cl. 336—136)

This invention relates to adjustable or variable inductors, particularly for use at radio frequencies.

One object of the present invention is to provide a new and improved adjustable inductor which will be capable of precise adjustment and will maintain its adjustment under all operating conditions.

A further object is to provide a new and improved adjustable inductor which is extremely compact yet is capable of providing a high inductance value.

Another object is to provide a new and improved adjustable inductor which is highly efficient and is adequately protected against vibration and moisture.

Further objects and advantages of the present invention will appear from the following description, taken with the accompanying drawings, in which:

FIG. 1 is a longitudinal section of an adjustable inductor to be described as an illustrative embodiment of the present invention, the section being taken generally along the line 1—1 in FIG. 4.

FIG. 2 is a plan view of the inductor of FIG. 1.

FIGS. 3 and 4 are transverse sections, taken generally along the lines 3—3 and 4—4 in FIG. 1.

As already indicated, FIGS. 1—4 illustrate an adjustable or variable inductor 1 which in some cases may also take the form of a transformer. The illustrated inductor 1 comprises a coil or winding 2 mounted on a spool or bobbin 3. When it is desired to provide a transformer rather than a simple inductor, two or more windings may be mounted on the spool 3. As shown, the spool 3 is received around a generally cylindrical tube or form 4. Both the spool 3 and the form 4 may be made of insulating material.

To increase the inductance and efficiency of the coil 2, and also to provide magnetic shielding, the inductor 1 comprises a pair of cup-shaped shell members 5 made of low-loss magnetic material such as various ferrite compositions, powdered iron, or the like. Such low-loss magnetic materials will be well known to those skilled in the art. Each of the cup-shaped members 5 may comprise a generally circular end wall 6 formed integrally with a substantially cylindrical side wall 7. It will be seen that each side wall 7 is formed with a flat annular end face 8.

The cup-shaped members are axially aligned and positioned opposite each other so that the end faces 8 of the side walls 7 are in abutment with each other. Thus, the cup-shaped magnetic members 5 define a space 9 within the side walls 7 and between the end walls 6. The coil 2 is received within the space 9 so that the magnetic members 5 provide a housing around the coil.

In this case, each end wall 16 is formed with an axial bore 10 which is received around the insulating tube or form 4. Thus, the magnetic circuit provided by the magnetic members 5 is interrupted by an air gap or space between the portions of the end wall 6 around the bores 10. To provide for adjustment of the inductance of the coil 2, a core or slug 11 is movable axially within the coil 2. In this case the core 11 is slidable within the insulated tube 4 which supports the coil 2. The core 11 is preferably made of low-loss magnetic material, such as various ferrite compositions, powdered iron or the like. However, in some cases the core 11 may be made of a conductive material, such as copper, silver-plated brass, or the like.

2

In order that the core 11 may be precisely adjusted, the illustrated core is provided with a threaded stud 12 which extends axially from one end of the core. The other end of the illustrated core 11 is formed with a screwdriver slot 27, or some other tool receiving formation so that the core may be adjusted by inserting an appropriate tool through the lower end of the insulating tube 4.

In the illustrated construction, the threaded stud 12 is screwed through an internally threaded bore 13 in a supporting member or disk 14 adjacent one end of the tube or form 4. Thus, the core 11 may be adjusted along the inside of the form 4 by rotating the threaded stud 12. A flat end portion 15 may be provided on the stud 12 to receive a slotted wrench or other tool so as to facilitate the adjustment of the core 11. It will be realized that the flat end portion 15 may be replaced with any other suitable tool receiving formation.

In this case, the inductor 1 is provided with a conductive outer housing 16 which serves as an electrostatic shield for the coil 2. The illustrated housing 16 has a flat circular upper end wall, which is formed integrally with a substantially cylindrical side wall 18. The lower end of the side wall 18 may be open to provide for insertion of the various components of the inductor into the housing 16. A terminal supporting disk or plate 19 may be mounted within the lower portion of the side wall 18. The illustrated disk 19 has an opening 20 which is received around the insulating tube 4. Two or more terminals or leads 21 may be mounted in the disk 19 for establishing electrical connections to the ends of the coil 2. The disk 19 may be made of various plastics or other insulating materials.

To protect the inductor 1 against moisture and vibration, all unoccupied spaces within the housing 16 may be filled with a suitable potting compound 22 composed of insulating material. Such potting compounds will be well known to those skilled in the art. The potting compound 22 retains the form 4, the cup-shaped members 5, the supporting disk 14, and the terminal plate 19 within the housing 16. As shown to advantage in FIG. 3, the cup-shaped members 5 may be formed with slots 23 which permit the potting compound to fill the unoccupied space around the coil 2 and within the cup-shaped members 5. Thus, the coil 2 is solidly anchored within the cup-shaped members 5.

It will be seen that the end wall 17 of the housing 16 is formed with an enlarged circular opening 24 around the threaded stud or stem 12. To lock the stud 12 after it has been adjusted, a threaded disk or nut 25 is screwed onto the stud and is adapted to be tightened against the supporting disk 14. The opening 24 is sufficiently large to receive the nut 25 so that the nut may be screwed into the opening. The nut 25 may be made of a thickness corresponding to that of the wall 17 so that the nut will be fully received or recessed within the opening 24 when the nut is tightened down against the disk 14.

To provide for easy operation by a suitable tool, the illustrated nut 25 is formed with a pair of openings 26 spaced outwardly from the threaded stud 12. The points of a pair of tweezers or some other tool may be inserted into the openings so that the nut 25 may easily be tightened and loosened.

The inductance of the coil 2 may be adjusted to the desired value by rotating the screw stud 12 so as to move the core 11 within the coil. Then the nut 25 may be tightened against the disk 14 to maintain the adjustment of the stud 12. In some cases, it may be desirable to clip off the projecting upper portion of the stud 12 so that the stud will not project to any substantial extent above the housing 16. The core 11 may also

be adjusted by inserting a screwdriver upwardly through the insulating form 4.

Various other modifications, alternative constructions and equivalents may be employed without departing from the true spirit and scope of the invention, as exemplified in the foregoing description and defined in the following claim.

I claim:

An adjustable inductor, comprising the combination of a pair of cup-shaped members made of low-loss ferrite magnetic material, each of said members having a substantially circular end wall connected to a substantially cylindrical side wall, each of said end walls having an axial bore therein, said cup-shaped members being positioned opposite each other with said cylindrical side walls disposed end to end to form a generally cylindrical space within said side walls and between said end walls, an insulating tube positioned within said space and extending through said axial bores in said end walls, a coil mounted on the outside of said tube and disposed in said space within said cup-shaped members, a substantially cylindrical core made of low-loss ferrite magnetic material and movable inside said tube and within said coil for changing the inductance thereof, a disc having one side engaging one end of said insulating tube, said disc having a threaded bore therein disposed opposite the end of said tube and along the axis thereof, a threaded metal stud secured to and projecting from one end of said core and threaded through said

threaded bore in said disc for moving said core along the inside of said tube, a metal housing mounted around said cup-shaped members and having an end wall engaging said disc on the opposite side thereof from said insulating tube, a mass of potting compound filling said housing and occupying the spaces therein around said cup-shaped members and said insulating tube to retain said tube and said cup-shaped members in said housing, said end wall of said metal housing having an axial opening therein around said stud, and a nut threaded onto said stud and engageable with said disc for locking the adjustment of said stud, said axial opening in said end wall of said housing being larger than said nut for freely receiving said nut, said nut having a thickness corresponding to the thickness of said end wall of said housing and being substantially flush with said end wall of said housing when said nut is engaged with said disc.
